Paul J. Eaton
ATTORNEY.

INVENTOR:

HARVEY T. BLACK

UNITED STATES PATENT OFFICE

HARVEY T. BLACK, OF LEXINGTON, NORTH CAROLINA

DOOR-OPERATING MECHANISM

Application filed January 10, 1930. Serial No. 419,871.

This invention relates to a garage or other building which is adapted to have doors which are automatically swung open and automatically closed by an automobile or other vehicle entering or being brought out of the same.

An object of my invention is to provide automatic means for opening and closing the doors of a garage and other building and for locking the doors in position when an automobile is stored therein.

Another object of my invention is to provide a simple and improved door actuating device which may be installed at moderate expense, and which will automatically actuate to open the doors of a garage and will automatically operate to close the doors of the garage by the pressure of the wheels of an automobile.

Some of the objects of my invention having been stated other objects will appear as the description proceeds when taken in connection with the accompanying drawings, in which—

25 Figure 1 is a plan view of the lower portion of a garage and the approach thereto showing my invention;

Figure 2 is a cross-sectional view taken along the line 2—2 in Figure 1;

30 Figure 3 is a view taken along the same line as in Figure 2 but showing the doors in opened position;

Figure 4 is a perspective view looking from the inside of the garage and showing the doors being swung to opened position;

Figure 5 is an enlarged perspective view of the guiding means at each end of my device for actuating the doors.

Referring more specifically to the drawings the numeral 10 indicates the side wall portions of a garage and the numeral 11 indicates the rear wall portion while the floor portion is indicated by the reference character 12. At the front portion of side walls 10 the conventional doors 13 and 14 are hingedly mounted as at 15 and 16 on posts 17 and 18, and although I have shown posts I desire it to be understood that these doors can be hingedly connected in any desired manner to the side walls of the garage or if de-

sired the side walls can be spaced further apart and short end walls project inwardly to a point where the doors may be desired to be hinged. The side wall of the garage on one side thereof has a smaller door 19 by means of which access to the interior of the garage may be had in order to allow the driver of the automobile to leave the garage after the car has been placed therein and the doors locked in position and also to permit the driver to enter the garage for the purpose of taking the car out of the same.

In front of the garage I have the two run ways 20 and 21 and if desired these run ways may be extended to a point where they meet each other, and in fact these run ways 20 and 21 may be made all in one piece and extend all the way across the entrance portion 22. These run ways are provided to serve as automatic means for supporting the car as it is driven into and out of the garage, and beneath these run ways means are provided for opening and closing the doors 13 and 14 which mechanism comprises the compression

70 springs 24 and 25, which are secured to a base plate 26 which is embedded in concrete or any other suitable material 27 and this concrete if necessary can be extended inwardly to make a base to support the floor 12 of the garage, or if desired the floor 12 may be dispensed with 75 and the concrete may serve as a floor. This base 26 has secured at each end thereof a U-shaped member 28 as appears in Figure 5, and to each end of the members 20 or 21 as the case

80 may be the downwardly projecting member 29 is secured which is adapted to slide within the U-shaped member 28 to prevent the members 20 or 21 from tilting sidewise when the wheels of the automobile may be located at 85 one side thereof. Mounted on the base plate 26 is a bearing member 30, and in this a lever 31 is pivoted as at 32, and the other end of this lever is pivoted as at 33 to a bell crank lever 34 which is integral with a transversely disposed shaft 35 which extends all the way 90 across the entrance portion 22, so as to connect the mechanism associated with members 20 and 21 together for operation so that if the mechanism connected with either of the members becomes broken that the mechanism as 95 100

sociated with the other members 20 or 21 will automatically operate both doors.

The member 30 has a member 36 pivotally connected thereto as at 37, this member 36 being fixedly secured to the lower face of the members 20 or 21 as the case may be.

At each end of the shaft 35 bell crank levers 40 and 41 are provided which project rearwardly and have links 42 and 43 secured thereto which links project upwardly and have their free ends secured to the staples 47 which are secured in the doors 13 and 14.

Holes 50 and 51 are provided in the floor portion of the garage through which the levers 40 and 41 and the links 42 and 43 are adapted to operate. The shaft 35 is rotatably mounted in the bearing members 53 which are secured to the base plate 26 to rotatably support the shaft in proper position.

Secured to the lower side of members 20 and 21 and at the ends thereof are the link or chain members 55 which limit the upward movement of the members 20 and 21 so that they can not move upward beyond a given point, as the springs 24 and 25 normally force these members upwardly.

On each of the base members 26 are secured by means of hinges such as 59 the block members 60 and 61, which are normally pulled backwardly to the position shown in Figure 2 by means of the tension spring 62, and to the other side of these block members 60 and 61 eye members 64 are secured and to these eye members the cord, cable, rod or other suitable member 66 is secured, which runs forwardly and passes through channel portion 67 in the concrete beneath the floor member 12 back to the transversely disposed channel 68 which extends all the way across the garage, and in the base portion of this channel 68 is mounted a bearing member 69 in which a rod 70 is rotatably mounted, and this rod 70 has upwardly projecting levers 71 fixedly secured thereto to which the other end of the cord, cable, rod or the like which is designated by the reference character 66 is secured. Near the central portion of the garage a hole 74 is provided in the floor 12 and a lever 75 projects upwardly through this hole, the lower end of the lever is fixedly secured to the transversely disposed shaft or rod 70. This lever 75 is of such a length so that the upper end thereof is adapted to press against the bumper or front axle of an automobile when the same is driven into the garage, so that when the doors close in behind the automobile when it is driven off of the members 20 or 21 and onto the floor portion 12, and the doors are swung to closed position

60 by means of the springs 24 and 25 pushing the mechanism back to the position shown in Figure 2, that the front axle or bumper of the automobile will engage the lever 75 and push the same to the dotted line position shown in Figure 2, and this will elevate the block mem-

bers 60 and 61 so as to prevent any other automobile or any other means from being placed on the ramp members 20 and 21 to open the doors. These block members 60 and 61 insure that the doors can not be opened as long as the automobile is within the garage and is driven against the lever member 75.

It is thus seen that when an automobile is driven onto the ramp members 20 and 21 that it will depress one end thereof and this will cause the parts to assume the position shown in Figure 3 and will open the doors, and when the automobile is driven into the garage and off of the ramp members 20 and 21 the springs 24 and 25 will press the parts back to normal position as shown in Figure 2 and the doors will close due to the pressure exerted by springs 24 and 25.

In the drawings and specification I have set forth a preferred embodiment of my invention, and although specific terms are employed they are used in a generic and descriptive sense only, and not for purposes of limitation, the scope of the invention being set forth in the appended claims.

I claim:

1. Means for automatically opening and closing a door and locking the same in position when in closed position comprising a depressible platform, resilient means mounted beneath the platform adapted to normally press the same upwardly, means for limiting the upward movement of the platform, a lever pivotally mounted at one end to a fixed object, a transversely disposed shaft, a bell crank lever mounted on said first named transversely disposed shaft, the other end of said lever being slidably and pivotally connected with the said bell crank lever, said lever being pivotally connected intermediate its ends to the said platform, a second bell crank lever mounted on said transversely disposed shaft, a link connecting said second bell crank lever with the said door, all of said means being adapted to automatically open the door when the platform is depressed and to close the door when the platform returns to normal position.

2. In a building having a plurality of swinging doors, means for automatically opening and closing said doors and for locking the doors in closed position, said means comprising two ramps or runways on which the wheels of an automobile are adapted to be driven and supported, compression springs mounted beneath said ramps and being adapted to press the same upwardly to normal position, means for limiting the upward movement of said ramps, a transversely disposed shaft, means associated with said ramps and said shaft adapted to partially rotate said shaft when said ramps are depressed, means associated with said transversely disposed shaft and the doors adapted to open the doors when the ramp is depressed to impart a par-

tial revolution to the transversely disposed shaft, said means being adapted to return to normal position to close the door when the ramp returns to normal position, a pivoted member mounted beneath said ramp, and having a connection leading to the rear portion of the building to which said doors are secured, a pivoted lever associated with said connection leading from said pivoted means, said lever being adapted to raise the pivoted means when pressed to the rearward to cause the ramp to be locked against depression while the lever and pivoted members are in raised position.

15 3. Means for automatically opening and closing a door comprising a resiliently supported ramp member, means for limiting the upward movement of said ramp member, a lever pivotally mounted at one end to a fixed support, a transversely disposed shaft, a bell crank lever on said transversely disposed shaft, a slideable and pivotal connection between said bell crank lever and said first named lever, means for securing the intermediate portion of said lever to the lower portion of said ramp, a second bell crank lever mounted on said transversely disposed shaft, a link connecting the free end of said second bell crank lever to a door of a garage, said parts being adapted to automatically open the door when the ramp is depressed, and being adapted to automatically close the door when the ramp returns to normal position, and means for locking the ramp against depression when the doors are in closed position.

In testimony whereof I affix my signature.
HARVEY T. BLACK.
